UNITED STATES PATENT OFFICE

156,759

TECHNICIAN'S WORKBENCH

Frank J. Omo, Houston, Tex., assignor to Alfab
Manufacturing Company, Houston, Tex., a cor-
poration

Application October 20, 1947, Serial No. 142,016

Term of patent 14 years

(Cl. D33—7)

To all whom it may concern:

Be it known that I, Frank J. Omo, a citizen of the United States of America, residing at Houston, Harris County, State of Texas, have invented a new, original, and ornamental Design for a Technician's Work Bench, of which the following is a specification, reference being made to the accompanying drawing, forming a part thereof.

Figure 1 of the drawings is a perspective view of the front and one side of a technician's work bench, showing my new design.

Fig. 2 of the drawings is a perspective view of the rear and the other side of my new design.

I claim:

The ornamental design for a technician's work bench, substantially as shown and described.

FRANK J. OMO.
